UNITED STATES PATENT OFFICE

107,176

DESIGN FOR A FLOWER HOLDER OR SIMILAR ARTICLE

Harold Joseph Meyer, Galesburg, Ill., assignor to Western Stoneware Company, Monmouth, Ill., a corporation of Maine

Application August 20, 1936, Serial No. 64,491

Term of patent 7 years

To all whom it may concern:

Be it known that I, Harold Joseph Meyer, a citizen of the United States and a resident of the city of Galesburg, county of Knox, and State of Illinois, have invented a new, original, and ornamental Design for a Flower Holder or Similar Article, of which the following is a specification, reference being had to the accompanying drawing, forming a part thereof.

On the drawing:

The figure is an isometric view of the flower holder showing my new design.

I claim:

The ornamental design for a flower holder or similar article, as shown.

HAROLD JOSEPH MEYER.
